UNITED STATES PATENT OFFICE.

GUSTAV JOHNSON, OF WEST ROXBURY, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

DUST CAP FOR LUBRICATING APPARATUS.

Application filed November 18, 1924. Serial No. 750,594.

This invention aims to provide an improved dust cap for use with lubricant-receiving nipples.

In the drawings, which illustrate a preferred and two modified embodiments of my invention:

Figure 1 is a side elevation of the preferred form of cap shown attached to a lubricant-receiving nipple;

Fig. 2 is a section on the line 2—2 of Fig. 1, being partly in elevation;

Fig. 3 is a section on the line 3—3 of Fig. 2;

Fig. 4 is a side elevation of a modified form of resilient member adapted to fit in any conveniently shaped casing;

Fig. 5 is an end view of the part shown in Fig. 4;

Fig. 6 is a transverse section of a second modified form of cap; and

Fig. 7 is an end view of the resilient means used in connection with the second modified form of cap shown in Fig. 6.

Referring to the preferred form of my invention, illustrated in Figs. 1 through 3, I have shown a dust cap for use in connection with lubricant-receiving nipples to exclude dust and dirt therefrom.

The preferred form of nipple, as illustrated, is provided with a threaded central portion 5 for engagement with the nozzle of a lubricant-expelling gun. At one side of the central portion 5 is a fine threaded portion 7 for securing the nipple to the part 35 to be lubricated and at the other side of the central portion 5 is a cylindrical portion 9 for engagement by the sealing element of a lubricant-expelling gun. The nipple is also provided with a neck 11, located between the central portion 5 and the cylindrical portion 9, for cooperation with the resilient means in the dust cap to retain the dust cap in position upon the nipple.

The preferred form of dust cap, as illustrated, includes a casing pressed from two pieces of sheet metal and also includes a relatively narrow strip of metal 12, which is held between the two pieces of the cap as best illustrated in Fig. 2. One of the pieces 50 of the cap provides a skirt portion 13, adapted to cover the threads of the central portion 5 and the same piece also presents an enlarged cylindrical portion 15, which presents at its outer end a flange 17 for cooper-

ation with the other piece of the cap which 55 presents a closed end 19 at one end thereof and a flange 21 rolled over the flange 17 to provide a finger hold 23 by which to remove the cap from the nipple.

The strip 12 is preferably formed from a 60 flat relatively thin strip of metal so as to fit the closed end 19 and then project upward to fit and be held between the flanges 21 and 17, respectively, of the casing parts, as illustrated. The free ends of the resilient member extend from between the flanges 17 and 21 toward the open end of the casing, terminating at the end of the enlarged cylindrical portion 15 to provide resilient jaws 25 and 27 for engagement with the neck 11 provided on the nipple. The extreme ends of the resilient member 12 extend upwardly from the jaws 25 and 27 to provide cams 29 and 31, which engage the end of the nipple, when the cap is being applied thereto 70 so as to expand the jaws 25 and 27 to permit entrance of the nipple within the cap. The enlarged portion 15 is provided so as to permit expansion of the jaws when the cap is being applied to the nipple or disengaged 75 therefrom, the jaws riding along the surface of the cylindrical portion 9 of the nipple until they snap into engagement with the neck 11.

Thus I have provided a dust-excluding 85 cap which is simple, inexpensive and durable in construction, and which may be easily attached and detached from a lubricant-receiving nipple and will remain in position upon the nipple until manually removed 90 therefrom.

Referring now to the modified form of my invention illustrated in Figs. 4 and 5, I have shown a resilient member 33 adapted to be used in connection with a casing similar to that shown in Figs. 1, 2 and 3, but wherein the finger grip is located adjacent the closed end of the cap. This form of resilient member is preferably pressed from a flat sheet of metal and is provided with a plurality of contractible and expandible arms 35 provided with neck-engaging jaws 37 and cam-shaped ends 41, substantially as shown and described in connection with the preferred embodiment of my invention.

A third form of dust cap is illustrated in Figs. 6 and 7, and this cap is pressed from two pieces of metal, one of which presents a

skirt 43 for covering the central portion 5 of the nipple, and an enlarged portion 45 presenting a flange 47. The cooperating piece 51 of the cap presents a flange 49 over which is rolled a portion of the flange 47 to form a finger grip 52, which may be located in any convenient position between the skirt 43 and the closed end of the cap member 51.

The resilient arms, in this form of cap, are formed integral with the cap member 51 and bent downwardly and rearwardly from the flange 49, and present neck-engaging jaws and cam ends substantially as shown and described in connection with the preferred embodiment of my invention.

While I have shown and described a preferred and two modified forms of my invention, it will be understood that I have done so for clarification only and, while I have shown a preferred form of nipple, it should be understood that my invention is not necessarily limited to use with such a nipple, my invention being best defined in the appended claims.

I claim—

1. A dust cap for a lubricant-receiving nipple including a casing having a skirt portion, a closed end, an enlarged cylindrical portion between said skirt portion and said closed end, a finger grip formed by interlocking flanges on said enlarged portion and said closed end, and a plurality of neck-engaging jaws within said casing adjacent said enlarged portion, said jaws free to expand and contract for engagement and disengagement with a neck provided in a nipple.

2. A dust cap for a lubricant-receiving nipple including a casing having a skirt portion, a closed end, an enlarged cylindrical portion between said skirt portion and said closed end, a finger grip formed by interlocking flanges on said enlarged portion and said closed end, and a plurality of resilient fingers extending from said finger grip and presenting neck-engaging jaws at their free ends for securing said casing to a nipple.

3. A dust cap for a lubricant-receiving nipple comprising, in combination, a two-piece casing secured together by flanges to form a finger grip and a third member within said casing rigidly clamped between the two parts of said casing, said third member presenting resilient fingers substantially parallel to the axis of said casing and said fingers presenting cam portions and neck-engaging jaws for cooperating with a nipple to secure said casing thereto.

4. A dust cap for a lubricant-receiving nipple comprising, in combination, a two-piece casing secured together by flanges and presenting an enlarged cylindrical barrel portion adjacent the neck provided in a nipple and a plurality of resilient neck-engaging fingers within said casing and substantially parallel with the axis of said enlarged barrel portion and spaced away therefrom to permit expansion thereof when engaging and disengaging the neck of the nipple.

In testimony whereof, I have signed my name to this specification.

GUSTAV JOHNSON.
